CLAIM

The ornamental design for a PH meter, as shown and described.

DESCRIPTION

FIG. 1 is a perspective view of a main body of a PH meter showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged top plan view thereof;

FIG. 10 is an enlarged bottom plan view thereof;

FIG. 11 is an enlarged view of portion 11 shown in FIG. 1;

FIG. 12 is an enlarged view of portion 12 shown in FIG. 2;

FIG. 13 is a perspective view of two heads of the PH meter shown separately for ease of illustration;

FIG. 14 is another perspective view thereof;

FIG. 15 is a front elevational view thereof;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof;

FIG. 21 is a perspective view of the main body and a first head of the PH meter where the first head is assembled with the main body; and,

FIG. 22 is a perspective view of the main body and a second head of the PH meter where the second head is assembled with the main body.

The dash-dash broken lines in the drawings depict portions of the PH meter that form no part of the claimed design. The

(Continued)

dot-dash broken lines in the drawings depict boundaries of the enlarged portions of the PH meter that form no part of the claimed design.
